UNITED STATES PATENT OFFICE.

EDGAR C. MOLBY, OF BROOKLYN, NEW YORK, ASSIGNOR TO IRON PRODUCTS CORPORATION, OF NEW YORK, N. Y., A CORPORATION OF DELAWARE.

HEATER.

Application filed May 9, 1921. Serial No. 468,028.

My invention relates to heaters, particularly of the down or cross draft type, and comprises means for controlling the drafts and also for varying the width of the combustion zone so as to permit the use of different kinds of fuel in the heater. In my improved heater convenient access is given to the combustion zone both for slicing and cleaning out purposes. My invention also comprises the construction and arrangement of parts which I shall hereinafter describe and claim.

Fig. 1 is an elevation, partly in section, of a heater embodying my invention; Figs. 2 and 3 are, respectively, sections on lines II-II and III-III of Fig. 1; and Fig. 4 is an elevation, partly broken away, of the front of the heater.

Referring to the drawings, the heater is comprised of a plurality of water sections 2 connected at top and bottom by the nipples 3, and between and through the water sections are arranged the flues 4, which lead out of the gas chamber 5. The combustion chamber 5 is arranged between the legs 6 of the water sections, which diverge upwardly from the lower connecting nipples 3. The legs 6 are provided with passageways 7 through which the air and burning gases pass from the furnace chamber 8 to the combustion chamber 5. The legs 6 have projections 9 which limit and determine the size of the passages 7. The furnace chambers 8, of which I have shown one on each side of the heater, are arranged between the water legs and a movable sectional grate 10. Above each grate 10 and alined therewith is a corresponding water front 23 connected with the water section 2. The upper connection is indicated at 24^a (see Fig. 4), and the lower connection is made by pipes 24 and connection 24^b. Thus the water fronts form a part of the water heating space of the heater, as is usual. Fuel is supplied to the furnace chambers from the fuel reservoirs 11 by gravity. Each movable grate 10 is pivoted at its upper end 12 and is capable of adjustment toward and away from the water legs so as to increase or diminish the width of the furnace chambers 8 by means of the rack 13 and pawl 14, which is attached to the lower end of the grate 10. The fuel in the furnace chamber 8 is supported upon the rotary grate bars 15. Access to

the ash pit 16 is provided through the door 55 17, and to the fire through and below the movable grate through the door 18. Air for combustion is preferably supplied through the draft door 19, but may also be supplied through the door 21.

In operating my improved heater, after a fire has been kindled on the grate bars 15 fuel is fed in through the door 20 at the top of the fuel chamber 11. Air for combustion passes through the draft door 19 and 65 through and beneath the movable grate 10 and also upward through the revolving grate bars 15, as is indicated by the arrows in Fig. 1. To provide as complete control as possible of the draft, I have shown a damper 70 22 by which the air admitted through the draft door 19 may be regulated or cut off entirely from the grate 15. If it is desired to supply air separately through the grate 15, this may be admitted through the door 75 21. As the coal burns away in the combustion zone 8 the unburned coal from the magazine 11 above drops down and thereby supplies fresh coal for combustion. The burning gases pass off through the passages 7 80 between the water legs 6 into the combustion chamber 5 and thence out through the flues 4 between and through the water sections 2.

I have found that my improved form of heater is very efficient in service and may be advantageously employed with either fine or coarse fuels, by reason of the free downward feed of the fuel, the control of the drafts, and the ability to widen or narrow the effective width of the combustion chamber by 85 moving the grate 10. The grate 10 has also the advantage of being made in interfitting sections 10^a secured in the frame 10^b, which permits ready replacement of a section in case one becomes warped or is otherwise 90 damaged. This is accomplished by constructing the frame 10^b in sections releasably connected together as indicated at 10^c. The removal of either end member of the frame 10^b permits the sections 10^a to be removed 100 and interchanged or replaced.

The terms and expressions which I have employed are used as terms of description and not of limitation, and I have no intention, in the use of such terms and expressions, of excluding any mechanical equivalents of the features shown and described, or portions thereof, but recognize that va-

rious structural modifications are possible within the scope of the invention claimed.

What I claim is:

1. In a sectional heater, the combination
5 of a water front; a sectional, approximately
vertically disposed grate forming with the
water front one side of the fuel chamber,
said grate being adjustable in a generally
10 horizontal direction independently of the
water front; a bottom grate; a plurality of
water legs opposite said front and said vertical
grate, said legs being spaced apart at
their lower ends opposite said grate to afford
15 draft passages, the parts so far enumerated
forming a fuel magazine and beneath this
a cross-draft fire pot; and releasable means
for fixing said vertical grate in adjusted
positions suited to the nature and condition
20 of the fuel, said means being capable of
manipulation while the heater is in opera- 20
tion.

2. In a heater, the combination of a plurality of water sections formed with passages for products of combustion leading past the lower portions of the sections; a 25 water front opposed thereto and spaced therefrom to form a gravity feeding fuel magazine; a sectional grate opposed to the lower portions of said water sections and hinged at its upper margin to define a cross- 30 draft fire pot beneath said magazine and adjustable in its dimension in the direction of draft; and releasable means for fixing the lower margin of said grate in adjusted 35 positions, said means being capable of manipulation while the heater is in operation.

EDGAR C. MOLBY.
